DESIGN FOR A BUCKET CART

Arthur C. Rapp, Merced County, Calif.

Application August 26, 1946, Serial No. 132,848

Term of patent 14 years

(Cl. D14—3)

To all whom it may concern:

Be it known that I, Arthur C. Rapp, a citizen of the United States, residing in the county of Merced, State of California, have invented a new original and ornamental Design for a Bucket Cart of which the following is a specification, reference being had to the accompanying drawing, forming a part thereof.

The figure on the drawing is a perspective view of a bucket cart, showing my new design.

I claim:

The ornamental design for a bucket cart, as shown.

ARTHUR C. RAPP.
